(57) **CLAIM**

The ornamental design for a bottle cap, as shown and described.

DESCRIPTION

FIG. 1 is an isometric view of a bottle cap showing our new design;

FIG. 2 is a front end view of the design of FIG. 1;
FIG. 3 is a rear end view of the design of FIG. 1;
FIG. 4 is a right side view of the design of FIG. 1;
FIG. 5 is a left side view of the design of FIG. 1;
FIG. 6 is a top view of the design of FIG. 1;
FIG. 7 is a bottom view of the design of FIG. 1;
FIG. 8 is an isometric view of the design of FIG. 1 shown in an open position;

FIG. 9 is a front end view thereof;
FIG. 10 is a rear end view thereof;
FIG. 11 is a right side view thereof;
FIG. 12 is a left side view thereof;
FIG. 13 is a top view thereof; and,
FIG. 14 is a bottom view; thereof.

The broken lines illustrate the environmental structure and form no part of the claimed design.

1 Claim, 11 Drawing Sheets
